CLASP FOR A NECKTIE OR THE LIKE

John L. Buchanan, Royal Oak, Mich.
(4912 Ogden Ave., Detroit, Mich. 48210)

Filed Dec. 6, 1967, Ser. No. 9,654

Term of patent 14 years

(Cl. D2—428)

FIG. 1

FIG. 2

FIG. 4

FIG. 3

FIG. 5

FIG. 6

FIG. 1 is a front perspective view of a clasp for a necktie showing my new design, the broken line showing of a necktie being for purposes of illustration only;

FIG. 2 is a side elevational view of the clasp of FIG. 1;

FIG. 3 is a sectional view in the direction of 3—3 of FIG. 2;

FIG. 4 is a bottom plan view thereof;

FIG. 5 is a second embodiment of the design of FIG. 1 wherein the head of the screw portion is hexagonal; and

FIG. 6 is a third embodiment of the design of FIG. 1 wherein the head of the screw portion is round and plain.

I claim:

The ornamental design for a clasp for a necktie or the like, as shown and described.
